US00D724143S

(12) **United States Design Patent**
Krause et al.

(10) **Patent No.:** US D724,143 S
(45) **Date of Patent:** ** Mar. 10, 2015

(54) **FOLDABLE MULTIPLE CAPNOGRAPHY DISPLAY**

(71) Applicants: **Gary Krause**, Racine, WI (US); **Mark Spangenberg**, Racine, WI (US)

(72) Inventors: **Gary Krause**, Racine, WI (US); **Mark Spangenberg**, Racine, WI (US)

(73) Assignee: **EKG Concepts, LLC**, Racine, WI (US)

(**) Term: **14 Years**

(21) Appl. No.: **29/469,236**

(22) Filed: **Oct. 8, 2013**

(51) LOC (10) Cl. 19-07

(52) U.S. Cl. USPC **D19/62**

(58) **Field of Classification Search**

USPC D19/59-64, 1, 21; D24/186, 167;
434/262, 236; 283/115; 351/242

See application file for complete search history.

(57) **CLAIM**

We claim the ornamental design for a foldable multiple capnography display, as shown and described.

DESCRIPTION

FIG. 1 is a front perspective view of a foldable multiple capnography display showing my new design;

FIG. 2 is a rear perspective view of the claimed design of FIG. 1;

FIG. 3 is a front perspective view of the claimed design of FIG. 1 in a partially folded position;

FIG. 4 is a rear perspective view of the claimed design of FIG. 1 in a partially folded position;

FIG. 5 is a front view of the claimed design of FIG. 1;

FIG. 6 is a rear view of the claimed design of FIG. 1;

FIG. 7 is a left side view of the claimed design of FIG. 1;

FIG. 8 is a right side view of the claimed design of FIG. 1;

FIG. 9 is a top view of the claimed design of FIG. 1; and,

FIG. 10 is a bottom view of the claimed design of FIG. 1.

The broken lines shown in the drawings are for purposes of illustrating portions of the design that form no part of the claimed design.

1 Claim, 4 Drawing Sheets
